UNITED STATES PATENT OFFICE.

MICHAEL ARCANGELO CAPOBIANCO, OF GLEN COVE, NEW YORK.

ADJUSTABLE WRENCH.

1,413,516.

Specification of Letters Patent. Patented Apr. 18, 1922.

Application filed November 17, 1921. Serial No. 515,807.

To all whom it may concern:

Be it known that I, MICHAEL A. CAPOBIANCO, a citizen of the United States, and a resident of Glen Cove, in the county of 5 Nassau and State of New York, have invented a new and Improved Adjustable Wrench, of which the following is a full, clear, and exact description.

This invention relates to a wrench, and 10 has for an object the provision of a simple, strong, economically manufactured wrench especially adapted for use on automobiles.

A further object resides in the provision 15 of a wrench which can be packed or stored away in a very small compass and at the same time is capable of being adjusted for use in connection with a wide variety of sizes of nuts.

A further object resides in the provision 20 of means whereby the wrench can be very simply and quickly adjusted from one position into another with a minimum expenditure of time and labor on the part of the person using the wrench.

25 A still further object resides in the particular construction and arrangement of parts hereinafter described and claimed and shown in the accompanying drawings.

The invention is illustrated in the drawings, in which

Figure 1 is a side elevation of the wrench in one adjusted position.

Figure 2 is a similar view of the wrench in another adjusted position.

35 Figure 3 is a plan view of the wrench.

Figure 4 is a transverse vertical section taken on the line 4—4 of Figure 1.

Figure 5 is a partial side elevation of a modified form of wrench.

40 Figure 6 is a front elevation of this modification.

It should be understood that the embodiment of my invention shown in the drawings is a preferred embodiment, although various

45 modifications can be adopted in the construction and arrangement of the parts and the character of material used without departing from the general spirit of the invention as hereinafter set forth.

50 The invention comprises a wrench having a handle 1, which is integrally extended at one end to form a jaw member 2. The other jaw member 3 is detachably pivoted to the jaw member 2 on a pin 4 which is disposed

55 through suitable apertures formed in the two jaw members. This pin is constructed

in any suitable manner so that it can be readily placed in position and as easily removed therefrom, although the fit of the pin in the apertures is tight enough to cause it 60 to remain in place unless forcibly removed. The jaw members are constructed in any suitable manner and of any desired shape. For instance, in Figures 5 and 6 the ends of the jaw members, such as 5 and 6, are 65 formed to function as a socket wrench, whereas the jaw members in Figures 1, 2, 3 and 4 are formed as flat surfaces to act as an ordinary wrench.

On the inner faces of the jaw members 2 70 and 3 are disposed pins 7 and 8. These pins extend inwardly toward each other and are adapted to position the ends of a spring 9 which extends from one jaw member to the other and the tendency of which is to keep 75 the jaw members separated the widest possible distance. On the rear oppositely disposed faces of each jaw member is formed a plurality of indentations or grooves, such as 10. These grooves are adapted to receive 80 portions of a link 12, which by being disposed in the grooves at its ends, acts as a sort of latch to restrain the jaw members in any desired relative position against the tendency of the spring to disturb its position. 85 Consequently, it can be observed by consideration of Figures 1 and 2 that by merely moving the link 12 from engagement with one pair of grooves to engagement with other grooves, the jaws may be moved relative to 90 each other to adapt the opening between the engaging faces to any size of article with which they are to be used. It also can be readily perceived that this manipulation of the wrench can be effected with the use 95 of one hand alone, so that the wrench is adaptable for use under conditions where the operator's other hand may be busy.

When the wrench is not in use the link 12, the spring 9 and the pin 4 can be removed 100 and these parts together with the two jaw members can be packed or stored away in a very small compass so that they are not needlessly in the way. Furthermore, if any one of these parts breaks, a new part can be 105 bought at a very nominal figure to replace the broken one without buying an entirely new wrench.

It is apparent, therefore, that I have provided the above set forth simple, economically manufactured, strong and compact wrench capable of a wide range of adjust-

ment with a minimum expenditure of time and labor on the part of the manipulator thereof.

What I claim is:

- 5 An adjustable wrench which comprises a handle portion, a jaw portion integrally connected to one end of the handle portion and extending therefrom at an angle, a second jaw portion formed at one end in the form 10 of a yoke to embrace the handle portion substantially where the handle portion connects with the first mentioned jaw portion, said handle portion having at this point an aperture, said yoke also having an aperture, 15 a removable pin extending through the aper-

tures in the yoke and the handle portion to pivotally hold the second jaw portion to the handle portion, a spring disposed between the jaw portions tending to hold them apart, the outer edges of each of the jaw portions 20 adjacent the pivot pin being provided with a plurality of notches or grooves, and a link embracing the jaw portions and adjustably engaging in the notches or grooves to hold the jaw portions in an adjusted position 25 with respect to each other, said link being movable along the rows of notches to vary the distance between the jaw portions.

MICHAEL ARCANGELO CAPOBIANCO.
